UNITED STATES PATENT OFFICE.

WILLIAM ANDERSON, OF HEBBURN-ON-TYNE, ENGLAND, ASSIGNOR TO A. REYROLLE & COMPANY LIMITED, OF HEBBURN-ON-TYNE, ENGLAND, A COMPANY OF GREAT BRITAIN.

OIL-IMMERSED ELECTRIC SWITCH.

Application filed November 22, 1926, Serial No. 150,040, and in Great Britain January 8, 1926.

This invention relates to oil-immersed electric switches, and has for its object to provide an improved arrangement for quenching the arc formed when such a switch is 5 opened.

In the oil-immersed electric switch according to the invention the contacts, at which arcing takes place on the opening of the switch, are so arranged that the arc is moved 10 bodily away from the gases which rise through the oil. Thus the arc is preferably moved bodily downwards through the oil either after it has been drawn out by the separation of the contacts or while it is being drawn out thereby.

The movement of the arc may be brought about in various ways. Thus the arcing contacts may first move horizontally away from one another to draw out the arc and may 20 then both move vertically downwards carrying the arc with them. Again one of the contacts may be fixed, the other contact first moving horizontally away therefrom and then swinging downwards with a pivotal 25 motion about the fixed contact.

The horizontal and vertical movements of the contact or contacts are preferably combined together to take place simultaneously, so that the arc is moved bodily as 30 it is being drawn out. In this case the arcing contacts may be arranged to move downwards as they separate from one another. Thus they may be mounted respectively on pivoted arms which swing downwards and 35 outwards away from one another when the switch opens.

The efficiency of the arrangement according to the invention is believed to be due to the action of forcing the arc against a body 40 of oil and thereby quenching it, this action being more fully described below with reference to a preferred construction.

It will be understood that the arcing contacts above referred to may themselves be 45 the main contacts of the switch or may be additional to main contact brushes. In the latter case the brushes may be separately carried and may have a motion different from that of the arcing contacts. Thus for 50 example when the arcing contacts are carried on pivoted arms which swing outwards and downwards, the main contacts may comprise two fixed contact members and a vertically movable brush-member. Alternatively the 55 main contact brushes may also be carried on

the pivoted arms which carry the arcing contacts. Various other arrangements of separate main contacts and arcing contacts may also be employed. In all such cases the main contacts would be arranged to open 60 shortly before the arcing contacts, so that the latter carry the full current only for a very brief interval.

The invention may be carried into practice in various ways and is applicable both to 65 D. C. and to A. C. switches.

In the accompanying drawings,

Figure 1 is a sectional elevation of one practical construction of oil-immersed switch according to this invention,

Figure 2 is a section on the line 2-2 of Figure 1,

Figures 3 and 4 are views generally similar to Figure 1 but showing the switch contacts just opening and fully open respectively,

Figure 5 is an elevation partly in section on the line 5-5 of Figure 6 of another construction of oil-immersed switch also according to this invention,

Figure 6 is a section at right angles to Figure 5, and

Figures 7 and 8 are elevations partly in section on the line 7-7 of Figure 6, Figure 7 showing the contacts just opening and Figure 8 illustrating the fully open position.

All the figures are somewhat diagrammatic, details of construction not essential to the understanding of the invention being 90 omitted.

With reference first to Figures 1 and 2, A is the oil tank having mounted within it two rock shafts B and B¹. The shaft B carries two main contacts of which one is shown at 95 C (Figure 1) and the shaft B¹ carries two cooperating main contacts C¹ and C² (Figure 2). It will be understood that the other main contact carried by the shaft B is similar to the contact C. The contact arms are 100 insulated from the shafts and the two main contacts C¹ and C² carried by the shaft B¹ are connected to plugs, one of which is indicated at D in Figure 1 adapted for connection to a busbar socket. The details of the main connections are not in themselves essential to the invention but it will be understood that in the example described the switch has two main breaks in series with each other. Each of the main contact arms 105 110

$C^1 C^2$ carries an auxiliary or arcing contact E cooperating with other arcing contacts E^1 pivotally mounted on the main contact C and on the other corresponding main contact 5 mounted on the shaft B . These arcing contacts are normally pressed by springs E^2 into engagement with the contacts E , the movement being limited in any suitable way.

For convenience and brevity the further 10 description will refer only to one cooperating pair of main contact arms, i. e. the contact arms C and C^1 of Figure 1, for it will be appreciated that the other pair is precisely similar and will operate in the same 15 way.

Each of the shafts B and B^1 has a crank F mounted upon it joined by a link F^1 to a rod F^2 carrying a piston or head F^3 working 20 in a cylinder F^5 and a kick-off spring F^4 tends to push the rod F^2 downwards to rock the shaft and open the switch contacts.

The mechanism for holding the contacts closed, for resetting and for reclosing them is shown in various positions in Figures 1, 25 3 and 4. The upper ends of the rods F^2 are joined by links F^6 to the arms of pivoted bell crank levers $G G^1$ which are coupled by a link H . The bell crank lever G^1 has an extension G^2 connected through a pivoted 30 link G^3 to the top of a long link or connecting rod J , the lower end of this rod being pivoted to a crank K on a spindle K^1 which can be partially rotated by means of a hand wheel K^2 and bevel gear K^3 . 35 Actually there are two rods J as shown in Figure 2 but that detail is immaterial. At a point J^1 (Figure 3) distant from the top of the rod J by a length equal to that of the link G^3 a link L is pivoted to the rod J , its other end being joined through a link 40 L^1 to the pivotal spindle of the bell crank lever G^1 . The links L and L^1 form a toggle which when set retains the other parts of the mechanism in the desired relative 45 position. M is a fixed stop which prevents rotation of the crank K in a clock-wise direction beyond a predetermined point.

In the closed position shown in Figure 1 the springs F^4 are tending to force down 50 the rods F^2 but they cannot do so as the toggle $L L^1$ is in its set position and the upper end of the rod J cannot swing outwards; thus the bell crank G^1 cannot be rotated.

To release the switch and allow it to open 55 the toggle $L L^1$ is broken, as for instance by being pushed up by the tripping electro-magnet N . This allows the rod J to swing out and consequently the bell crank G^1 can rotate. Figure 3 shows the position of the parts just after the trip has occurred.

The rods F^2 continue their rapid downward motion and the contacts assume their 60 fully open position as shown in Figure 4 but as yet the crank K and rod J remain

practically in the position shown in Figure 3.

Resetting of the mechanism ready for reclosing is accomplished by rotating the crank K counter-clockwise from the position of Figure 3 to that of Figure 4. This motion brings the link G^3 parallel with the rod J and sets the toggle $L L^1$ again and rotation of the crank K clock-wise back until it meets the stop M brings all the parts 75 back to the closed position of Figure 1.

In order to bring the moving parts quickly to rest in the open position a hole F^7 in the wall of the cylinder F^5 is closed by the piston or head F^3 just as it reaches the 80 limit of its downward movement.

Dealing now with the motion of the contacts themselves, it will be seen that the initial opening movement first separates the main contacts $C C^1$ but momentarily the arcing contacts $E E^1$ remain closed as shown in Figure 3. Further movement separates the arcing contacts and draws the arc rapidly outwards at the same time moving it down quickly away from gas bubbles which naturally rise. The magnetic forces also tend to force the arc downwards and thus the arc is drawn rapidly downwards both mechanically and magnetically away from the conducting gas bubbles and is broken over what is practically a solid body of oil since the inertia of the oil is too great to admit of its rapid acceleration when confined by the tank. The breaking of the arc is assisted by means of an arc splitter O of refractory insulating material projecting upwards from the floor of the tank between the separating contacts. The main functions of this arc splitter O are to lengthen and cool the arc and to assist in preventing movement of the oil with the contacts away from the arc. Since the limiting factor for the speed of break is the cavitation which may be set up in the oil by the movement of the contact arms, it will be seen that the 100 employment of the two movable pivoted arms allows nearly twice the speed of break which is possible without risk of cavitation when a single moving contact is used.

Figures 5, 6, 7 and 8 show another practical construction of switch according to this invention intended for heavier currents. The chief difference between this form and that previously described is that the arcing contacts are not carried by the main contact 110 arms but are mounted separately.

In this construction the movable main contact is in the form of a block C^4 mounted on but insulated from a plunger rod F^8 which tends to be moved downwards by a 120 kick-off spring F^9 to break the circuit by separating the block C^4 from two fixed main contacts C^4 .

The arcing contacts $E^8 E^4$ are pivotally mounted on arms $E^5 E^6$ carried by but in- 130

sulated from rock shafts B^2 B^3 . Springs E' tend to press the contacts E^3 E^4 together, the motion being limited by stop pins E^5 .

The ends of the main contact block C^3 are joined by insulating rods C^5 to crank blocks B^4 on the rock shafts B^2 B^3 so that the downward opening movement of the main contact causes a rapid downward and outward swing of the arms E^5 E^6 and the 10 arcing contacts carried by them.

The various stages of the opening movement are clearly shown in Figures 7 and 8 from which it will be seen that the drawing-out and breaking movement of the arc 15 is essentially the same as that described with reference to Figures 1, 2, 3 and 4.

The arcing contacts are separated from the main contacts by an insulating partition P (removed for the sake of clearness 20 in Figure 8) and an arc splitter O^1 is provided. A chamber R (Figure 6) receives the ascending gas which can pass out through vent pipes R^1 .

The mechanism for resetting and reclosing need not be described in great detail 25 as it is substantially the same as that described with reference to Figures 1, 2, 3 and 4. The top of the rod F^8 is linked to a pivoted cross head G^4 joined by a link G^5 to the top of a rod J^2 and the top of 30 that rod is joined by a toggle link L^2 L^3 to the pivot of the cross head. The rod J^2 is in this construction divided or compound, its upper part being connected to 35 its lower part by a spring J^3 (Figure 6) serving to provide a yielding contact between the moving block C^3 and the fixed block C^4 . The lower end of the rod J^2 is pivoted to a crank K^4 operated through gear 40 K^5 by a hand wheel K^6 .

The two rock shafts B^2 B^3 are shown as coupled by a rod B^5 but this coupling is not essential if each of the shafts is connected to the block C^3 as at C^5 .

In this construction also some provision 45 is preferably made for bringing the moving parts quickly to rest and as will be seen from Figure 6 a tapered plug F^{10} on the rod F^8 enters into a clearance space in 50 a block F^{11} in a cylinder F^{12} this forming a dashpot arrangement.

This cylinder F^{12} is surrounded by an insulating layer F^{13} , and the two fixed main contacts C^4 are clamped together around 55 this insulation F^{13} by means of insulated bolts C^6 .

It is to be understood that the foregoing description has been given by way of example only and that considerable modifications in detail may be made without departing from the scope of the invention. 60

What I claim as my invention and desire to secure by Letters Patent is:—

1. In an electric switch the combination of a tank adapted to contain oil, rock shafts 65 in said tank, arms mounted on said rock shafts, arcing contacts mounted on said arms, fixed and movable main contacts in said tank, an insulating partition in said tank between said arcing contacts and said 70 fixed and movable main contacts, a spring tending to separate said movable main contact from the fixed main contacts, a toggle linkage operating to hold the main contacts closed against the action of said spring, a trip device for breaking said toggle linkage 75 and allowing the spring to operate, an operative connection between said movable main contact and said rock shafts, such operative connection acting to rock the shafts 80 immediately after the main contacts are broken and thus to swing the arms and arcing contacts downwards and outwards, and an arc splitter in the path of the arc as it is moved downwards and drawn out between said arcing contacts. 85

2. In an electric switch the combination of a tank adapted to contain oil, rock shafts 90 in said tank, arms mounted on said rock shafts, arcing contacts mounted on said arms, fixed and movable main contacts in said tank, a spring tending to separate said movable main contact from the fixed main contacts, a toggle linkage operating to hold the main contacts closed against the action 95 of said spring, a trip device for breaking said toggle linkage and allowing the spring to operate, an operative connection between said movable main contact and said rock shafts, such operative connection acting to 100 rock the shafts immediately after the main contacts are broken and thus to swing the arms and arcing contacts downwards and outwards, an arc splitter in the path of the arc as it is moved downwards and drawn out 105 between said arcing contacts, and dash-pot mechanism for bringing the moving contacts quickly to rest.

In testimony whereof I have signed my name to this specification.

WILLIAM ANDERSON.
